(57) **CLAIM**

The ornamental design for an electromagnetic driving pilot valve, as shown and described.

DESCRIPTION

FIG. 1 is a front, top, and left side perspective view of an electromagnetic driving pilot valve;

FIG. 2 is a rear, bottom, and right side perspective view thereof;

FIG. 3 is a front elevational view thereof, the rear elevational view being symmetrical to the front elevational view;

FIG. 4 is a top plan view thereof;

FIG. 5 is a bottom plan view thereof;

FIG. 6 is a left side elevational view thereof; and,

FIG. 7 is a right side elevational view thereof.

The broken lines shown in the figures are for the purpose of illustrating portions of the electromagnetic driving pilot valve that form no part of the claimed design.
